UNITED STATES PATENT OFFICE.

THOMAS SHIPLEY, OF YORK, PENNSYLVANIA.

MEANS FOR SEPARATING OIL FROM THE REFRIGERANT IN REFRIGERATING SYSTEMS.

Application filed January 4, 1924. Serial No. 684,348.

To all whom it may concern:

Be it known that I, THOMAS SHIPLEY, a citizen of the United States, residing at York, in the county of York and State of Pennsylvania, have invented certain new and useful Improvements in Means for Separating Oil from the Refrigerant in Refrigerating Systems, of which the following is a specification.

10 This invention relates to refrigeration, and particularly to means for removing oil and the like from ammonia and other refrigerant gas.

In a prior application, Serial No. 666,196, 15 filed October 2, 1923, I describe and claim a method of and means for separating oil from the refrigerant in refrigerating systems, and the present application relates to a modified form of apparatus for carrying out 20 the method aforesaid.

The apparatus forming the subject of the present application is particularly adapted for use with compressors of the two-stage type.

25 The difficulties arising from the congelation of lubricating oil in the expansion valve and in the cooling coils of refrigerating systems are well known. The broad principle involved in the prior application, above 30 identified, involved the removal of the oil by the interposition of a strainer or filter in the path of the liquefied refrigerant as the latter leaves the condenser. Such a filter necessarily offers resistance to the flow of the 35 liquefied refrigerant and it therefore becomes necessary to provide for a pressure drop through the filter. In the prior application this result is secured by the use of a supplemental cooler interposed in the liquid refrigerant line on the discharge side of 40 the filter, operating to produce a temperature drop corresponding to the desired pressure drop through the filter, and thus serving to prevent evaporation of any portion of 45 the liquid refrigerant despite the pressure drop.

The present invention relates to a special 50 form of apparatus in which this pressure drop is secured by connecting the discharge side of the filter to the intermediate receiver forming a part of a two-stage compression system. In such a system the intermediate pressure is determined by the number of compressions and the ratio between the high

and low pressure cylinders, but since this 55 pressure is lower than high pressure receiver pressure, part of the liquid refrigerant in the intermediate receiver will vaporize and by such vaporization cool the remainder. Thus, as in the prior application, we have 60 two stages of cooling of the refrigerant, the first in the condenser and the second in the intermediate receiver, and between these cooling stages the refrigerant is maintained in liquid form and filtered under an effective 65 pressure corresponding to the temperature difference.

The accompanying drawing illustrates in diagram a preferred embodiment of the invention as applied to one well known type, 70 of refrigerating system.

The parts can best be identified by tracing out the path of the refrigerant in the system.

Liquefied refrigerant passes from the intermediate receiver 1 through the cold liquid line 2 to the expansion valve 3, through 75 which it expands into the cooling coil 4. The coil 4 is submerged in the usual brine tank 5 and acts to chill the brine.

The evaporated refrigerant flows by way 80 of pipe 6 to a trap 7, which separates and collects any entrained liquid refrigerant, and returns it by way of pipe 8 to the coil 4. The remaining gaseous refrigerant thus freed of 85 entrained liquid passes by way of the low pressure suction line 9 to the low pressure compressor 10, where it is compressed. It passes thence by the pipe 11 to the intermediate pressure gas cooler 12 where it is 90 cooled by water or other cooling agency circulated in the coil 13.

From the gas cooler 12 the gas passes by 95 the high pressure suction line 14 to the high pressure compressor 16 where it is compressed further. A branch connection 15 from the top of intermediate receiver 1 leads to the high pressure suction line. This ensures the existence of high pressure suction pressure in the intermediate receiver and causes vaporization of a part of the liquid refrigerant in the receiver and the consequent cooling of the liquid refrigerant 100 therein to the corresponding temperature.

From high pressure cylinder 16 the refrigerant flows by the high pressure discharge line 17 to the condenser 18, where it is cooled 105 and liquefied.

All the parts so far described are familiar

to those skilled in the art and illustrate one known type of installation using a two-stage compressor. The details are subject to considerable variation. The present invention

5 involves the path of the refrigerant from the condenser 18 to the intermediate receiver 1.

From the bottom of condenser 18 liquid refrigerant flows by gravity to the high 10 pressure liquid receiver 19. Thence it flows to a gravity oil separating trap 20, of usual form, provided with gage glasses 21 and a valved oil-draw-off connection 22. From the top of trap 20 the refrigerant flows through 15 one or the other of two filter heads 23 which are provided each with valves 24 and 25, to permit them to be connected in the refrigerant line or cut out in alternation so that one may be cleaned while the other is in use. 20 A pump-out connection for the filter heads is shown at 26.

From the filter 23 the refrigerant flows through pipe 27 and reducing valve 28 to the intermediate receiver 1. The low pressure cylinder operates to maintain the desired low pressure in the refrigerating coils 4 and delivers the refrigerant at a higher pressure to the intermediate pressure gas cooler where it is partially cooled. The high 30 pressure cylinder 16 compresses the refrigerant flowing from the intermediate pressure gas cooler and delivers it to the condenser 18. It also withdraws gaseous refrigerant through the pipe 15 from the receiver 1.

The refrigerant is cooled and liquefied by the condenser 18 under high pressure discharge pressure, and is accumulated in liquid form, under that pressure, in the high pressure receiver 19 and oil separating trap 20. The filter and the reducing valve 28 operate conjointly to maintain the desired differential pressure between the high pressure receiver and the intermediate receiver 1. 45 A part of this differential pressure does the work of forcing the liquefied refrigerant through the filter in the head 23. The reason for using the reducing valve is to adjust the rate of flow to the intermediate receiver.

50 The invention is not restricted to any particular type of filter head 23, as any filter capable of operating under the available effective pressure, and of passing a liquid refrigerant such as anhydrous ammonia, 55 while preventing the passage of lubricating oil may be used. The high and low pressure compressors may be separate compressors, each driven independently of the other at the proper rate, or the two may be connected as in the conventional type of two-stage compressors.

60 The invention has peculiar advantages because the oil is removed in a cool part of the system where the oil is in a liquid condition. This permits a substantially complete

elimination of the oil and virtually precludes the accumulation of congealed oil in the expansion valve and in the cooling coils.

What is claimed is:

1. The combination with a refrigerating 70 system of the compressor condenser evaporator circuit type, including two compressor stages and an intermediate receiver subject to the suction pressure of the high pressure stage, and connected to receive liquefied refrigerant from the condenser and to feed it to the evaporator, of an oil removing filter interposed in the refrigerant line between the condenser and the intermediate receiver. 75

2. The combination with a refrigerating 80 system of the compressor condenser evaporator circuit type, including two compressor stages and an intermediate receiver subject to the suction pressure of the high pressure stage, and connected to receive liquefied refrigerant from the condenser and to feed it to the evaporator, of an oil separating trap and an oil removing filter interposed in the refrigerant line in the order stated 85 between the condenser and the intermediate receiver. 90

3. The combination with a refrigerating system of the compressor condenser evaporator circuit type, including two compressor stages and an intermediate receiver subject 95 to the suction pressure of the high pressure stage, and connected to receive liquefied refrigerant from the condenser and to feed it to the evaporator, of an oil removing filter and a pressure reducing valve interposed in the refrigerant line between the condenser and the intermediate receiver. 100

4. The combination with a refrigerating system of the compressor condenser evaporator circuit type, including two compressor 105 stages and an intermediate receiver subject to the suction pressure of the high pressure stage, and connected to receive liquefied refrigerant from the condenser and to feed it to the evaporator, of an oil separating trap, an oil removing filter and a pressure reducing valve interposed in the order stated 110 in the refrigerant line between the condenser and the intermediate receiver.

5. In a refrigerating system, the combination 115 of a receiver, an evaporator fed by the receiver, two compressor stages connected in series to withdraw gaseous refrigerant from the evaporator, a condenser connected to receive compressed refrigerant from the second compressor stage, a connection between said receiver and a point in the refrigerant line between the two stages of the compressor, whereby the receiver is maintained at interstage pressure, a connection for feeding liquefied refrigerant from the condenser 120 to said receiver and an oil removing filter interposed in the last named connection. 125

6. The combination with a refrigerating 130 system of the compressor condenser evapo-

rator circuit type, including two compressor stages and an intermediate receiver connected to the refrigerant line between stages and arranged to feed liquefied refrigerant to the evaporator, of a pressure reducing connection for conveying liquefied refrigerant from the condenser to the receiver and including an oil removing filter.

7. The combination with a refrigerating system of the compressor condenser evaporator circuit type, including two compressor stages, a high pressure receiver arranged to receive liquefied refrigerant at condenser

pressure and an intermediate receiver maintained at a lower pressure and temperature 15 than the high pressure receiver, by means of the evaporation of the liquefied refrigerant from said intermediate receiver into the refrigerant line at a point intermediate the two compression stages, of a pressure reducing connection between the high pressure receiver and the intermediate receiver, said connection including an oil removing filter.

In testimony whereof I have signed my name to this specification.

THOMAS SHIPLEY.
